UNITED STATES PATENT OFFICE.

EDWARD N. KERN, OF PORTSMOUTH, OHIO.

LIQUID-FUEL-DISPENSING APPARATUS.

1,210,811.

Specification of Letters Patent. Patented Jan. 3, 1917.

Application filed November 27, 1915. Serial No. 63,876.

To all whom it may concern:

Be it known that I, EDWARD N. KERN, a citizen of the United States, residing at Portsmouth, in the county of Scioto and State of Ohio, have invented certain new and useful Improvements in Liquid-Fuel-Dispensing Apparatus, of which the following is a specification, reference being had to the accompanying drawings.

This invention relates to certain improvements in liquid fuel dispensing apparatus and is an improvement on the invention as embodied in my prior Patent No. 1,177,870, dated April 4, 1916; and it is an object of the invention to provide a dispensing apparatus of this general character having novel and improved means whereby the quantity of liquid to be dispensed may be determined with convenience and facility.

The invention consists in the details of construction and in the combination and arrangement of the several parts of my improved apparatus whereby certain important advantages are attained and the device is rendered simpler, less expensive and otherwise more convenient and advantageous for use, all as will be hereinafter more fully set forth.

The novel features of the invention will be carefully defined in the appended claim.

In order that my invention may be the better understood, I will now proceed to describe the same with reference to the accompanying drawings, wherein—

Figure 1 is a view partly in elevation and partly in section illustrating a liquid dispensing apparatus constructed in accordance with an embodiment of my invention; and Fig. 2 is an enlarged sectional view taken through the upper end portion of the return pipe and the guide member coacting therewith.

As disclosed in the accompanying drawings, 1 denotes a measuring tank in communication, through the medium of the pipe 2, with a suitable source of liquid supply 3, herein indicated as a tank, embedded within the ground and said pipe 2 discharges within the tank a predetermined distance above the base thereof although I do not wish to limit myself in the present embodiment of my invention to this exact arrangement. Interposed within the pipe 2 is a pump 4 preferably of a centrifugal type operated by a conventional electric motor M in electrical connection with a suitable source of

energy, said connection having interposed therem a cut-out switch S, for a purpose which is believed to be self-evident.

Extending within the tank 1 through the base thereof is an endwise movable return pipe 5, herein disclosed as slidably arranged within the bushing 6 depending from the base of the tank 1 and having its lower end portion telescopically engaged with the stand 7 in communication with the tank 3, whereby it will be perceived that the excess liquid delivered within the tank 1 may return to the tank 3. It is to be understood that the position of the upper end of the pipe 5 determines the level of the liquid within the tank 1.

Depending from the top of the tank 1 is the guide rod 8 provided with the longitudinally disposed radial ribs or flanges 9, said rod 8 and flanges 9 being disposed within the upper end of the pipe 5 and affording an effective means to assure the maintenance of the pipe 5 in operative position. It will also be observed that the frictional contact between the pipe 5 and the bushing 6 serves to maintain the return pipe 5 in its various endwise or vertical adjustments.

10 denotes a scale disposed vertically of the tank 1 and arranged on an outer face thereof, said scale being graduated into gallons and coacting with said scale is the index or pointer 11 provided at the upper extremity of the rod 12 mounted for sliding movement within the bracket or bearing 14 and having its lower extremity provided with an angular extension 15 secured to the return pipe 5 at a predetermined point thereon so that said extension will not interfere with the endwise movement of the pipe 5 in either direction. It is to be noted that the index or pointer 11 is arranged in the same horizontal plane as the top or upper extremity of the pipe 5 so that upon adjusting the pipe 5, it may be readily determined from the scale 10 the quantity of liquid to be retained in the tank 1. As herein embodied, the index is shown as positioned to indicate eight gallons and it will be appreciated that any amount in excess of eight gallons which may be pumped or otherwise delivered within the tank 1 will be carried out through the return pipe 5. The pipe 5 is also provided at a predetermined point below the bottom of the measuring tank 1 with the hand grasp or handle 16 so that

desired endwise movement may be imparted to the pipe 5. It will be noted that the coaction between the rod 12 and its guide 14 serves to maintain the pipe 5 against axial rotation, and thereby maintaining the hand grasp or handle 16 in a predetermined position.

In the present application, I have described, in the main, only the features constituting the improvement over my prior patent. It is to be understood that the parts illustrated in the accompanying drawings but not hereinbefore specifically referred to or described, are substantially identical to corresponding parts comprised in my prior patent, although it may be well to state that 17 denotes a flexible discharge tube in communication with the interior of the measuring tank 1 and provided at its outer end with 20 a nozzle 18 of conventional construction, for a purpose which is clearly obvious to those skilled in the art to which my invention appertains.

From the foregoing description, it is thought to be obvious that an apparatus constructed in accordance with my invention is of an extremely simple and comparatively inexpensive nature and is particularly well adapted for use by reason of the convenience and facility with which it may be assembled, and it will also be obvious that my invention is susceptible of some change and

modification without material departure from the principles and spirit thereof and for this reason I do not wish to be understood as limiting myself to the precise arrangement and formation of the several parts herein shown in carrying out my invention in practice.

I claim:

In combination with a reservoir in communication with a suitable source of supply, a vertically disposed return pipe extending within the reservoir and mounted for endwise movement, an index member having its lower end secured to the return pipe at a point below the reservoir, the upper end portion of said member overlying an outer face of the reservoir, a hand grasp extending laterally from the return pipe for imparting endwise movement thereto, a scale arranged on the outer face of the reservoir and with which the index member coacts, and a guide carried by the reservoir through which the index member is slidably disposed, said guide coacting with the index member for holding the return pipe against rotation.

In testimony whereof I hereunto affix my signature in the presence of two witnesses:

EDWARD N. KERN.

Witnesses:

WILLIAM E. KILCOYNE,
R. C. KILCOYNE.
